UNITED STATES PATENT OFFICE.

LOUIS A. MORTIMER, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed November 19, 1920. Serial No. 425,078.

To all whom it may concern:

Be it known that I, LOUIS A. MORTIMER, a citizen of the United States, residing at New York, in the county of New York, State of New York, have invented certain new and useful Improvements in Telephone-Exchange Systems, of which the following is a full, clear, concise, and exact description.

This invention relates to telephone exchange systems and more particularly to improved signaling arrangements for link circuits used in such systems.

It is an object of this invention to provide for a link circuit which is used to extend a connection from a cord circuit associated with one switchboard to a cord circuit of another switchboard, new and improved means for automatically causing the disconnection of ringing current from the cord circuit, immediately upon the actuation of the signaling device at the incoming end of the link circuit. Previously, it was necessary to maintain the ringing response relay in very careful adjustment so as to cause a reliable operation of the tripping relay in the cord circuit and the consequent disconnection of the ringing current.

To attain this object in accordance with a feature of this invention, a ringing response relay in a link circuit is made to control a second relay which connects across the line a tripping bridge momentarily but positively so as to cause a reliable disconnection of the ringing current.

This object is further attained in accordance with another feature of the invention by arranging a ringing response relay so that upon its complete operation its winding is included in a circuit of lower impedance than that in which it was before it begins to respond. This increases the reliability of the operation of the relay since it compensates for the shunting away of current through the tripping bridge connected across the circuit.

The invention will be understood from the following specification and accompanying drawing in which the figure shows a subscriber's station 27 connected to a line circuit A terminating at a switchboard from which a connection may be extended by means of a cord circuit B and link cir-

cuit C, to a cord circuit D at another switchboard, to which cord circuit a telephone 32 is connected. Although the figure shows only one subscriber's line circuit, one cord circuit and one link circuit, it will be understood that there may be a plurality of each of these, each similar to those shown. The cord circuit B is arranged so that when the plug 1 is inserted into the jack 2, a ringing response relay 3 operates from a source of grounded ringing current 19 associated with cord circuit B and through the contacts of a ringing relay 5 over the conductors of link circuit C. The operation of relay 3 causes the illumination of a lamp 4, the operation of a marginal tripping relay 16, and consequently the release of relay 5 and the discontinuance of ringing current. The operator in control of the cord circuit D responds to the illumination of lamp 4 by inserting a plug 6 into a jack 7 thereby extinguishing lamp 4.

It is thought that the invention will be more fully understood from the following description.

When the receiver at the subscriber's station 27 is removed from the switch hook to initiate a call, a lamp 8 is lighted in response to the usual operation of line relay 30. In response thereto, the operator in control of the cord circuit B inserts the plug 9 into jack 10. Cut off relay 29 operates to restore the line relay 30 and extinguish the lamp 8. Relay 11 operates and prevents the illumination of the supervisory lamp 12. Since these circuits are well known, and are not a part of this invention and are shown only to give a more complete description, details of operation are not given. The operator in answering actuates the listening key 13 and connects to the cord circuit a telephone set of the usual type (not shown). Upon ascertaining that the subscriber at station 27 desires a connection to be extended to the switchboard with which is associated the cord circuit D, the operator inserts plug 1 into jack 2. Relays 5 and 14 are then operated over the following path: from grounded battery through the winding of relay 5, normal contacts of relays 15 and 16, supervisory lamp 17, sleeve contacts of plug 1 and jack 2, and winding of relay 14 to ground. Relay 14 in operating discon-

ncts, at its normal contacts, the windings of relay 18 from the conductors of link circuit C to which conductors relay 5 in operating connects ringing current and causes the actuation of the ringing response relay 3 over the following circuit: from the source of grounded ringing current 19 through the winding of marginal relay 16, lower alternate contact of relay 5, ring contacts of plug 1 and jack 2, lower left-hand winding of repeating coil 24, normal contact of relay 21, condenser 20, winding of relay 3, upper left-hand winding of repeating coil 24, tip contacts of jack 2 and plug 1, through the upper alternate contact of relay 5 to ground. Relay 16 obtains insufficient current to operate through the circuit just traced. As soon as relay 3 closes its left-hand contacts the lower left hand winding of repeating coil 24 is short circuited over a path through the said left hand contacts of relay 3 and the left hand normal contacts of relay 21, thereby reducing the impedance of the ringing circuit. This change in impedance may trip relay 16 providing the ringing interval represented is a major part of the ringing period. If the time interval of this change in impedance is not of sufficient duration to operate relay 16 at this time, said relay will be operated during the next ringing period in a manner hereinafter described. Relay 3 in operating causes the operation of relay 21, and of lamp 4 through obvious circuits. Relay 21 in operating locks up through the following circuit: from grounded battery through the normal contact of relay 22, right-hand alternate contact of relay 21, and winding of relay 21 to ground. Accordingly, a momentary operation of relay 3 suffices to cause a steady illumination of the lamp 4 through the following circuit: from grounded battery through the normal contact of relay 22, right-hand alternate contact of relay 21 and lamp 4 to ground. The left-hand contacts of relay 21 are of the make-before-break type and are designed so that the alternate contact is closed before the normal contact is broken. Accordingly, relay 21 in operating, at the instant when all the left-hand contacts are together, momentarily bridges the resistance 23 across the tip and ring conductors of the link circuit C over the following path: from the tip conductor through resistance 23, the make-before-break contacts of relay 21 and thence in parallel one path extending through the left hand contacts of relay 3 to the ring conductor and the other path extending through the lower left-hand winding of repeating coil 24 to the ring conductor. The circuit through the lower left winding of the repeating coil is only momentary because when relay 21 is completely operated, the circuit through the repeating coil is broken at the normal

contact of relay 21. As soon as relay 21 is completely operated, and while relay 3 is still operated, the resistance 23 is also momentarily bridged across the conductors of the link circuit through the left-hand contact of relay 3, which increases the reliability of such tripping connection. 70

The resistance 23 being connected as described above, relay 16 now operates over the circuit previously traced for relay 3, 75 but which now includes the resistance 23 of low impedance, connected across the conductors as described above. Relay 16 by its operation removes the short-circuit from the winding of relay 15 which operates and 80 short-circuits the winding of relay 5, causing its release, and disconnecting ringing current from cord circuit B.

The operator in control of the link circuit D observes the illumination of lamp 4 85 and inserts plug 6 into jack 7 establishing a conversational connection with subscriber's station 27 and causing the operation, over an obvious circuit, of relay 22 which interrupts at its normal contact the locking circuit of relay 21, which relay releases and extinguishes the lamp 4. Relay 22 connects across the link circuit through its alternate contact, the resistance 31 which causes the operation of supervisory relay 25 over the 90 following circuit: from grounded battery through the winding of relay 25, lower normal contact of relay 5, ring contacts of plug 1 and jack 2, lower left hand winding of repeating coil 24, resistance 31, alternate 100 contact of relay 22, upper left hand winding of repeater coil 24, tip contacts of jack 2 and plug 1 and upper normal contact of relay 5 to ground. Relay 25 in operating places the shunt resistance 26 around the supervisory lamp 17, which extinguishes it, notifying the operator in control of the cord circuit B that the call has been answered. When the conversation is completed, plug 6 is withdrawn from jack 7, which releases 105 relay 22 and opens the bridge circuit including resistance 31, causing the release of supervisory relay 25 and the consequent illumination of lamp 17. In the usual manner the restoration of the receiver at station 27 causes the illumination of lamp 12. The operator in control of the cord circuit observing the illumination of both lamps, withdraws plugs 9 and 1, the sleeve relays release 110 and all apparatus is now restored to normal. 115

The link circuit C is so arranged that the operator in control of cord circuit D may initiate a call and have the connection extended by the operator in control of cord circuit B to the subscriber's station 27. This is accomplished by the insertion of plug 6 120 into jack 7 operating over the circuit previously traced therefor, relay 22 and bridging across the link conductors resistance 31 to operate the relay 18 and illuminate the 125 130

lamp 28. Cord circuit B is then used, to extend in the regular way, the connection to station 27.

What is claimed is:

- 5 1. In a telephone exchange system, a subscriber's cord circuit, a source of ringing current, a switchboard, a link circuit for extending a connection from said cord circuit to said switchboard, a signaling device associated with the link circuit, means for connecting the source to the link circuit, means responsive to the ringing current to operate said signaling device, a relay in the link circuit controlled by the ringing response 70 relay, and means controlled thereby to cause a disconnection of the source.
- 10 2. In a telephone exchange system, a subscriber's cord circuit, a source of ringing current, a switchboard, a link circuit for extending a connection from said cord circuit to said switchboard, means for connecting the ringing current to the link circuit, a relay responsive to the ringing current, a second relay controlled by the ringing response 75 relay means for causing the disconnection of the source and means controlled jointly by the said ringing response relay and said second relay to apply said disconnecting means.
- 15 3. In a telephone exchange system, a subscriber's cord circuit, a source of ringing current, a switchboard, a link circuit for extending a connection from said cord circuit to said switchboard, a signaling device associated with the link circuit, means for connecting such ringing current source to the link circuit, means responsive to the ringing current to operate said signaling device, additional means in the link circuit also 80 responsive to such ringing current to cause a disconnection of the source, and means for maintaining an operative circuit for said additional means independently of the ringing current.
- 20 4. In a telephone exchange system, a subscriber's cord circuit, a source of ringing current, a switchboard, a link circuit for extending a connection from said cord circuit to said switchboard, a signaling device associated with the link circuit, means for connecting said source to the link circuit, means comprising a relay responsive to the ringing current to operate said signaling device, another relay in the link circuit responsive 85 to the ringing current to cause a disconnection of the source, and means for maintaining an operative circuit for said second mentioned relay until the ringing current is disconnected.
- 25 5. In a telephone exchange system, a subscriber's cord circuit, a source of ringing current, a switchboard, a link circuit for extending a connection from said cord circuit to said switchboard, a signaling device associated with the link circuit, means for connecting said source to the link circuit, means for causing the disconnection of said source, a relay responsive to the ringing current to apply said disconnecting means, a second relay controlled by the ringing response 90 relay, an initial operating circuit for said ringing response relay, controlled by said second relay, a maintaining circuit for said ringing response relay, and means for closing said maintaining circuit before said initial operating circuit is opened.
- 30 6. In a telephone exchange system, a trunk circuit, means for establishing a connection therewith, a signaling circuit closed by the establishment of said connection, signal current responsive means actuated in response to the closure of said circuit, a relay and a signaling device operated in response to the actuation of said signal current responsive 95 means, and means controlled jointly by said signal current responsive means and said relay for rendering said signaling circuit ineffective.
- 35 7. In a telephone exchange system, a subscriber's line, a trunk line, means for establishing a connection therebetween, a signaling circuit closed by the establishment of said connection, signaling current responsive 100 means actuated in response to the closure of said circuit, a direct current bridge, a relay energized by the actuation of said signal current responsive means for connecting said bridge across said signaling circuit, a locking circuit for said relay completed in response to actuation thereof to maintain said bridge connected, and means controlled by said bridge for rendering said signaling circuit ineffective.
- 40 8. In a telephone exchange system, a subscriber's cord circuit, a source of ringing current, a switchboard, a link circuit for extending a connection from said cord circuit to said switchboard, a signaling device associated with the link circuit, means for connecting the source to the link circuit, means responsive to the ringing current to operate said signaling device, a relay in the link circuit controlled by the ringing response 105 relay, and means controlled thereby to cause a disconnection of the source.
- 45 9. In a telephone exchange system, a subscriber's cord circuit, a source of ringing current, a switchboard, a link circuit for extending a connection from said cord circuit to said switchboard, means for connecting the ringing current to the link circuit, a relay responsive to the ringing current, a second relay controlled by the ringing response 110 relay means for causing the disconnection of the source and means controlled jointly by the said ringing response relay and said second relay to apply said disconnecting means.
- 50 10. In a telephone exchange system, a subscriber's cord circuit, a source of ringing current, a switchboard, a link circuit for extending a connection from said cord circuit to said switchboard, a signaling device associated with the link circuit, means for connecting said source to the link circuit, means for causing the disconnection of said source, a relay responsive to the ringing current to apply said disconnecting means, a second relay controlled by the ringing response 115 relay, an initial operating circuit for said ringing response relay, controlled by said second relay, a maintaining circuit for said ringing response relay, and means for closing said maintaining circuit before said initial operating circuit is opened.
- 55 11. In a telephone exchange system, a subscriber's line, a trunk line, means for establishing a connection therebetween, a signaling circuit closed by the establishment of said connection, signaling current responsive means actuated in response to the closure of said circuit, a direct current bridge, a relay energized by the actuation of said signal current responsive means for connecting said bridge across said signaling circuit, a locking circuit for said relay completed in response to actuation thereof to maintain said bridge connected, and means controlled by said bridge for rendering said signaling circuit ineffective.
- 60 12. In a telephone exchange system, a subscriber's cord circuit, a source of ringing current, a switchboard, a link circuit for extending a connection from said cord circuit to said switchboard, a signaling device associated with the link circuit, means for connecting the source to the link circuit, means responsive to the ringing current to operate said signaling device, a relay in the link circuit controlled by the ringing response 120 relay, and means controlled thereby to cause a disconnection of the source.
- 65 13. In a telephone exchange system, a subscriber's cord circuit, a source of ringing current, a switchboard, a link circuit for extending a connection from said cord circuit to said switchboard, a signaling device associated with the link circuit, means for connecting the source to the link circuit, means responsive to the ringing current to operate said signaling device, a relay in the link circuit controlled by the ringing response 125 relay, and means controlled thereby to cause a disconnection of the source.

9. In a telephone exchange system, a subscriber's line, a trunk line, means for establishing a connection therebetween, a ringing circuit closed by the establishment of said connection, a relay in the trunk line actuated in response to the closure of said circuit, a second relay, a signal actuated in response to the operation of said first mentioned relay, and means controlled jointly by said first mentioned and said second relay for rendering said ringing circuit ineffective.
10. In a telephone exchange system, a trunk circuit, impedances in said trunk circuit, means for establishing a connection with said trunk circuit, means for estab-

lishing a signaling circuit by the establishment of said connection, signaling current responsive means actuated in response to the closure of said circuit for changing the impedance of said trunk circuit, a direct current bridge for said trunk circuit, a relay controlled by said signaling current responsive means for connecting said bridge across said trunk, and means controlled by the change in impedance of said trunk and the connection of said bridge for rendering the signaling circuit ineffective.

In witness whereof, I hereunto subscribe my name this 16th day of November A. D., 1920.

LOUIS A. MORTIMER.
